PEGBOARD MOUNTED SUPPORT FOR SCREWDRIVERS

Albert J. Enckler, North Olmsted, Ohio, assignor to
ABL Associates, Inc., Cleveland, Ohio

Filed Sept. 11, 1975, Ser. No. 602,455

Term of patent 14 years

Int. Cl. D6—04

U.S. Cl. D6—125

Fig. 1

Fig. 2

Fig. 3

FIG. 1 is a perspective view of a pegboard mounted support for screwdrivers showing my new design;
FIG. 2 is a front elevational view thereof; and
FIG. 3 is a side elevational view thereof.
I claim:

The ornamental design for a pegboard mounted support for screwdrivers, as shown and described.
